UNITED STATES PATENT OFFICE.

STEPHEN H. HASTINGS AND CLIFTON C. HALL, OF LITCHFIELD PARK, ARIZONA, AS
SIGNORS TO THE GOODYEAR TIRE & RUBBER COMPANY, OF AKRON, OHIO, A COR-
PORATION OF OHIO.

ATTACHMENT FOR COTTON GINS.

Application filed February 7, 1928. Serial No. 252,477.

Our invention relates to apparatus for ginning cotton and it has particular relation to an improvement of a portion of the apparatus that will facilitate the removal of ginned cotton therefrom.

One object of the invention is to provide a device that will remove ginned cotton from a ginning roller without tangling or matting the cotton.

Another object of the invention is to provide a device that will remove ginned cotton from a ginning roller in such manner that waste lint is reduced to a minimum, and, at the same time, so affecting the lint as to facilitate its subsequent handling.

Heretofore, cotton gins, especially those employed for ginning long staple cotton, were provided with stationary brushes that were mounted adjacent the ginning rollers for removing the lint therefrom. While these brushes performed their function to a certain extent, they caused the lint to become matted and tangled, and considerable quantities of the lint adhered to the ginning rollers. Therefore, samples having the desired characteristics were difficult to obtain. Also, by the employment of brushes so-called "back-lashing" occurred which caused considerable waste of the lint cotton. This waste sometimes amounted to at least 3 per cent of the output of the ginned cotton. An additional disadvantage resulting from the operation of the brush type roller was that the rollers became overheated.

By employing an apparatus according to this invention, the disadvantages referred to are obviated. The invention involves the application of a roller having a fluted or grooved surface, which is mounted adjacent the ginning roller and is provided with bearings so constructed that the position of the roller can be varied in both vertical and horizontal directions, in order that the rollers may assume their proper relation to each other.

Suitable driving connections are provided in conjunction with the mechanism that forms a part of a conventional cotton gin for operating a device embodying the invention. By utilizing a device of this kind, the ginning elements of the apparatus can be properly observed or inspected without interference from such obstacles as rollers or brushes having matted or tangled lint cotton thereon.

For a better understanding of the inven-

tion, reference may now be had to the accompanying drawings, forming a part of this application, of which:

Fig. 1 is an elevational view of a cotton gin embodying the invention;

Fig. 2 is a cross-sectional view of the gin taken substantially along the line II—II of Fig. 1; and

Fig. 3 is a perspective view, on a larger scale, of a bracket for supporting one of the rollers of the gin.

In practicing the invention, a cotton gin 10 is provided which comprises a frame 11 having a horizontally disposed crank shaft 12, mounted in the lower portion thereof and driven by a suitable source of power (not shown). One end of the crank shaft rigidly supports a relatively large grooved pulley 13. A belt 14 is trained about the pulley 13 and about a relatively smaller pulley 15 that is rigidly secured to one end portion of a horizontally disposed shaft 16. Journal bearings 17 support the shaft 16 adjacent the end portions thereof and have offset portions 18, through which bolts 19 are disposed and secured. These bolts extend through slotted portions 22 of angular brackets 23 and are adjustable horizontally therein. A vertical portion 24 of the bracket is provided with openings 25 for the reception of bolts 26 that are threaded into an end portion of arms or brackets 27 rigidly secured to, and forming a part of, the frame 11. A plurality of the bolt openings 25 which are preferably elongate in form, are arranged in parallel relation, thus providing means for vertically adjusting the position of the bracket 23.

A roller 28, having fluted portions or grooves 29 formed in the surface thereof is rigidly mounted upon the shaft 16 between the brackets 23. Preferably the grooves 29 are spaced and extend longitudinally of the roller 28, as shown, although it is apparent that they may assume other forms or shapes.

The arms 27 are provided with horizontal surfaces 32, upon each of which a bearing support 33 is slidably adjustable by means of a bolt 34 having one end thereof secured to the bearing support, as indicated at 35, and having its other end portion extending through the frame 11 and provided with an adjusting nut 36. Bearing blocks 37 which can be tightened by means of bolts 38, support a driven shaft 39 in spaced relation

to, and parallel with, the shaft 16. A ginning roller 42, rigidly secured about the shaft 39, is provided with a relatively smooth surface which is normally spaced approximately $\frac{3}{2}$ of an inch from the surface of the roller 28.

It will be observed that the axis of the roller 28 is slightly lower than the axis of the roller 42, and that the distance between these 10 rollers can be varied by manipulating the bearing elements 17, 23 and 33. Both of the rollers 28 and 42 are rotatably driven in the same direction, but the roller 42 is normally driven at a rate of approximately 140 R. P. 15 M. while the roller 28 is driven at the rate of approximately 1200 R. P. M.

The ginning operation is performed by a mechanism 43, which is actuated by means of crank arms 44 driven by the shaft 12. 20 Since this mechanism does not constitute a part of the invention, a detailed description thereof is not necessary. After the lint, indicated at 45, has been separated from the cotton seed, the roller 42 tends to move it 25 away from the mechanism 43. The grooved roller 28 which rotates at a relatively high rate of speed prevents the lint from adhering to the roller 42 and also prevents it from becoming matted and tangled. By the rapid 30 rotation of the roller 28, the grooves therein serve as partial vacuums, thereby facilitating the removal of the lint from the roller 42. Thus, during ginning operations the roller 28 causes continuous removal of the lint from 35 the roller 42.

From the foregoing description, it will be apparent that the invention constitutes a marked improvement over the types of devices previously employed for ginning cotton 40 and that the expense of operating such apparatus can be materially reduced by practicing the invention.

Although we have illustrated only one form which the invention may assume and 45 have described in detail but a single applica-

tion thereof, it will be apparent to those skilled in the art that it is not so limited but that various minor modifications may be made therein without departing from the spirit of the invention or from the scope of 50 the appended claims.

What we claim is:

1. The combination with a machine having means for ginning cotton including a driven ginning rigid roller, of a second roller 55 mounted upon the machine adjacent the ginning roller, the second mentioned roller having grooves formed in its surface longitudinally thereof.

2. The combination with a machine having means for ginning cotton including a driven ginning roller, of a second rigid roller 60 having grooves formed in its surface longitudinally thereof, a support for the rollers, and bearing brackets supporting the second 65 mentioned roller upon the support, said bracket being vertically adjustable along the support and a portion of the bracket carrying the second mentioned roller being horizontally adjustable upon the remaining portion 70 of the bracket.

3. The combination with a machine having means for ginning cotton including a driven ginning roller, of a second driven 75 rigid roller geared to rotate at a materially greater speed than the ginning roller, the second mentioned roller having grooves extending longitudinally in the surface thereof, a support for the rollers, and bearing brackets supporting the second mentioned 80 roller upon the support, each of said brackets being composed of two parts, the first part being vertically adjustable on said support and the second part being horizontally adjustable on the first part. 85

In witness whereof, we have hereunto signed our names.

STEPHEN H. HASTINGS.
CLIFTON C. HALL.
